MARTIN CASTRICUM, OF SPRINGFIELD, MASSACHUSETTS, ASSIGNOR TO THE FISK RUBBER COMPANY, OF CHICOOPEE FALLS, MASSACHUSETTS, A CORPORATION OF MASSACHUSETTS.

CORD-GUIDING DEVICE.

Application filed June 26, 1926. Serial No. 118,761.

The present invention relates to a cord guiding device particularly adapted for the production of weftless cord fabric. It has for its object a guiding device which will 5 facilitate changes being made in the spacing of the cords. It has for a further object the provision of a spacing device which will give the cords a definite spaced relation which will be constant and not dependent 10 upon measurements made by the workman.

Referring to the drawings,

Fig. 1 is a diagrammatic side elevation of a weftless cord unit embodying my improved guiding device;

Fig. 2 is a side elevation on a larger scale of some of the parts shown in Fig. 1;

Fig. 3 is a bottom plan view of the parts in Fig. 2, taken on line 3-3 of the latter figure; and

Fig. 4 is a view similar to Fig. 2 but showing the parts in different positions.

The cords *c* are led from the creel 10 through a thread board 11 to the customary tensioning and equalizing rolls 12. The web 15 of cords thus formed is passed around guide rolls 14 and 15 and through a spacing comb 16. This comb is preferably made adjustable and may be constructed in accordance with the disclosure of either of my prior 20 Patents 1,500,232, July 8, 1924, or 1,531,689, March 31, 1925. From the comb the cords pass the spacing device, which constitutes my present invention and which will be described later, and are pressed by roll 17, 25 preferably having a smooth surface, against the rubber sheet 18, on the calender roll 19. The calender has been shown as of the four roll type having in addition to roll 19, rolls 20, 21 and 22, all mounted in a frame 23. 30 Between rolls 19 and 22 is placed a feed of rubber 24 producing the sheet 18. Between rolls 20 and 21 is placed a feed of rubber 25 producing a sheet 26. The two sheets of rubber, together with the web of cords 13, 35 are passed between rolls 19 and 21 producing the composite sheet 27.

My improved spacing device is mounted upon brackets 28 carried by the frame of the calender. Journaled for rotation in 40 these brackets is a member 29 having ends 30 of reduced diameter, fitting in suitable bearings in the brackets. In these reduced ends are formed holes 31 which co-act with

a pin 32 releasably carried in a hole in the bearing. By this means the member 29 can 55 be held in any one of a number of desired positions.

Member 29 is provided with cord guiding and spacing portions 33, 34, 35 and 36, having grooves 40 corresponding to the cord 60 spacing desired. While these have been shown as four in number, the number may be varied without departing from the invention. Alternating with the guiding portions are smooth surfaces 37, preferably protruding somewhat from the body of the member 65 so that their elevation is sufficient to hold the cord web 13 clear of the adjacent guiding portions as in Fig. 4.

In use the cords are first threaded into the 70 machine while the member 29 is held by pin 32 in the position of Fig. 4. Comb 16 is adjusted to give the approximate spacing desired and then member 29 is rotated to bring the proper one of the guiding portions into 75 operation. In Fig. 2 the guiding portion 33 has been shown in use. During the running of the calender and the production of the fabric, the cords pass through the grooves 40 in guiding portion 33 and are placed by it 80 in accurate spaced relation on roll 17. If it is desired at any time to change the spacing, the member 29 is rotated into the position of Fig. 4 so that one of the smooth surfaces 37 is brought to the bottom, the surface 85 chosen being one of those adjacent the guiding portion to which change is to be made. The comb 16 may now be readjusted and the cords arranged evenly upon the smooth portion 37. The member 29 is now rotated to 90 bring the desired guiding portion lowermost and the cords directed into the grooves beginning at one side of the sheet and passing progressively across it.

Having thus described my invention, I 95 claim:

1. In the manufacture of weftless cord fabric, a cord guiding device of the type wherein a web of separate cords is arranged by a spacing device upon a smooth surfaced roll by which the web is pressed against the rubber, characterized by that construction of the spacing device which comprises a multi-sided member rotatably mounted so as to extend the full width of the web and having 100 alternate cord guiding portions and smooth 105

surfaces of sufficient elevation to hold the cords clear of the guiding portion, the several cord guiding portions having cord guiding grooves of different spacing in the 5 several portions, and means for holding the multi-sided member fixed against rotation so as to present any desired guiding or smooth portion to the web of cords.

2. A cord guiding device adapted for use 10 in the manufacture of a web of weftless cord fabric comprising a multi-sided bar extending the full width of the cord web, the several sides of the bar having cord guiding grooves of differing spacing, and being separated by smooth surfaces of sufficient eleva- 15

tion to free the cords from adjacent guiding grooves.

3. In the manufacture of weftless cord fabric, a cord guiding device of the type wherein a web of separate cords is arranged 20 by a spacing device upon a smooth surfaced roll by which the web is pressed against the rubber, characterized by the formation of the spacing device as a multi-sided member having alternate cord guiding portions and 25 smooth surfaces of sufficient elevation to hold the cords clear of the guiding portions, the several cord guiding portions being of a different spacing.

MARTIN CASTRICUM.
